PELORUS

Charles Arthur Clark, Portland, Oreg., assignor to
 Leupold & Stevens Instruments, Portland,
 Oreg., a partnership

Application June 30, 1943, Serial No. 492,969

5 Claims. (Cl. 240—2.1)

This invention is directed to an improvement in a navigation instrument of the pelorus type, wherein parallax is avoided, and wherein permanency of adjustment and illumination of the dial, and ease of manipulation in use, are essential features of the improvement.

An essential characteristic of the improvement is the provision of an indestructible opaque compass card, accurately centered and rigidly mounted, eliminating by its indestructibility the objectionable fragility of the glass or like transparent card usually employed in previous similar structures.

A particularly important feature of the improved construction is the control of the illumination of the card to a substantially limited area directly beneath the alidade sight wire, to restrict and confine the illumination to the reading area, and to utilize the alidade as the element for directing the illumination to thus insure restriction of illumination to the section of the card graduation being utilized at any particular time.

The invention is also directly concerned with the mountings, adjustments, and selective locking of the operative details, to provide for ease of manipulation, certainty and permanency of adjustment.

A typical form of the improved instrument will be described in detail, and is illustrated in the accompanying drawings, in which:

Figure 1 is a plan view of the improved instrument.

Figure 2 is a vertical section of the same.

Figure 3 is a plan view with the alidade removed, showing particularly the light-passage openings for controlling the passage of light rays to the alidade.

Figure 4 is a bottom plan view of the alidade.

Figure 5 is a section on line 5—5 of Figure 2.

Figure 6 is a section on line 6—6 of Figure 2.

Figure 7 is a similar view of the rear sight vane.

Figure 8 is a section on line 8—8 of Figure 7.

Figure 9 is a detail in elevation, showing the mounting of the outer gimbal ring in the arms of the supporting yoke, and

Figure 10 is a detail in elevation, partly in section, showing the mounting means for the inner gimbal ring.

The improved instrument includes a supporting yoke 1, the upstanding arms 2 of which extend from a central head 3, to be removably secured to an appropriate cap 4 by a set screw 5, said cap being secured at the end of an appropriate standard or tubular support as shown by dotted lines in Figure 2. Cooperating pins and depressions

6 on the respective members serve to accurately position and predetermine the set of the instrument.

The instrument proper is supported on an outer gimbal ring 7, having diametrically opposed pins 8, flattened on one side, as at 9 in Figure 9. The upper or free ends of the yoke arms 2 are formed with bearing slots 10, which are open at their upper ends, with the upper portions of the walls spaced to just permit the passage of the minor diameter of the pins 8. The lower spacing and shape of the walls of the slots 10 are formed to receive and act as a free bearing for the maximum diameters of the pins, all as shown more particularly in Figure 9. The outer gimbal ring is thus freely supported in the yoke arms and locked against separation except when the plane of such ring is in the plane of the arms 2.

The inner gimbal ring 11 is rotatably supported in the outer gimbal ring 7 at diametrically opposed points equally spaced from the pins 8 by pivot pins 12, which are threaded into the outer ring 7 and secured therein by lock nut 13. The pins are provided with appropriate pivot terminals to seat in openings 14 in the inner ring 11. This detail is more particularly shown in Figure 10. The inner gimbal ring is thus mounted for universal movement.

Inner ring 11 is provided with inwardly-extending spokes 16 which in turn support a central well member 15. Well member 15 is substantially closed at the bottom 17, and open at the top, with a completely closed annular side wall 18 of predetermined height. The bottom of the well is formed to receive a light socket 19, for a removable light bulb or other light source 20. Thus the light bulb 20 is disposed entirely within the well. A light switch 21 is removably secured to the under side of well member 15 and a service lead 22 is provided for energizing the light bulb under control of the switch. A relatively thin wall casing 23 is removably secured to the bottom of the well, by means of bolts 24, to enclose the switch and light socket. This casing is provided with a weight mass 25, which may be of lead, for maintaining inner ring 11 in level position.

The side wall of the well member 15 is formed at its upper end with an annular recess or shoulder 27. A hollow post 26 rises centrally from the bottom of the well to a height just below the horizontal plane of shoulder 27. A transparent plate 28 having a central opening of substantially the same diameter as that of the hollow post 26 rests on shoulder 27, overlying the light

bulb 20. Secured in hollow post 26 is a tube 26A which passes through the central opening of the transparent plate 28 and rises substantially above the horizontal plane of the gimbal ring 11, said tube being threaded at its upper end. A hollow cap 29 embraces the tube 26A, passes through the central opening in the transparent plate 28, and rests on the projecting end of the hollow post 26. The cap 29 is also circumferentially enlarged above the plate 28 to bear on said plate at 30 and the upper surface of said cap is provided with an annular recess 29A.

A compass card 31 of opaque material such as metal, preferably, but not necessarily, of nickel, silver, is provided with a central opening to receive a nipple 36 to which the card 31 is secured by nut or ring 33, the card being held or clamped between the nut or ring 33 and a circumferential enlargement 37 of the nipple 36. The nipple 36, and the card 31 slip over the tube 26A and the peripheral edge of the card is seated in an annular recess or shoulder 32 in the inner gimbal ring 11. The nut 33 rests within the recess 29A of cap 29, the central area of the card 31 resting on the upper surface of the cap 29. The under surface of the card bears also on the upper edge of the side wall 18 of the well and forms at this point, indicated at 34, a sealing barrier against light leakage from the well member. The upper surface of the card is appropriately marked, U. S. Navy type markings being shown. The nipple 36 extends above the card 31 as at 38 and is externally threaded for a purpose which will be explained hereinafter.

The card, in the area over the well member 15, is formed with light-passage openings 35. These are shown in annular series of relatively different diameters, as in Figure 3, but variations are contemplated. These openings provide the sole light-ray escape from the well.

An alidade 39 is formed with a central portion 40 having an opening 41 to receive nipple 36. The central portion 40, circular in plan, has an annular depending flange 42 on its lower surface substantially commensurate with the diameter of the upper edge of the wall 18 of the well member 15.

The alidade 39 has diametrically-opposed integral arm extensions 43 and 44, the former constituting the forward arm in use, while the latter is the rear arm. The arm 43 is formed at its free end with a sight opening 45 of nearly the full width of the arm but of less length than the length of the arm. The sight opening 45 is bridged centrally and longitudinally by a sight wire 46, terminally secured to the arm beyond the opening, which sight wire, while preferably of nylon, may be of hair or fine wire.

The lower surface of the arm 43, including an appropriate area of the underside of the central portion 40 of the alidade, is cut away at 47 to form a light channel. The light channel is preferably arched, as in Figure 6. It opens at its end remote from the center 40 directly to the sight opening 45, and terminates short of the opening 41 in the center, being gradually reduced in depth within the area of the center, as shown in Figure 4. The lower surface of the alidade arm 44 is flat and arranged to just clear the card 31, the arm being formed with a sight opening 45, as shown.

The outer or free ends of the alidade arms are provided with upstanding walls 48 and 49 respectively. The walls rise above the upper surfaces of the respective arms 43 and 44, and support the

respective sighting vanes 50 and 51, respectively. The vane 50 is hingedly connected at 52 for swinging in the plane of the arm in a direction towards the arm 51 and limited to a vertical position in the opposite direction. This vane 50 is of more or less conventional form having a relatively wide longitudinally-ranging slot 53, bridged by a central longitudinal hair line 54.

The usual level 55 is carried, preferably removably, in clips; and hingedly mounted at 56, immediately above the level, is a frame carrying a dark glass mirror 57, adapted to cooperate with the sights in the usual manner. The bubble is directly in the line of vision of the observer and can be fully seen while making a sight and without change of vision direction.

The vane 51 is hingedly connected at 58 to the wall 49, being movable inwardly toward vane 50 but limited to a vertical position in outward movement. This vane 51 is also more or less conventional, and formed, as shown in Figures 7 and 8, with a longitudinal arcuate depression 59, said depression terminating in a narrow slot 60.

25 A particularly important feature of the present invention resides in the formation of the alidade, whereby the visible lighted area is confined to the sight opening 45 and the proximate lower area of the sight vane 50. The described arrangement of the card and alidade makes clear that the light rays from the bulb 20 can only pass beyond the well 15 through the openings 35 in the card, and that beyond these openings, the only possible light path is through the light channel 47. The light rays passing to and through the channel 47 reach the sight opening 45 and illuminate the dial area of the card 31 for about twenty degrees of the arc directly beneath the sight wire 46. All other light passages to the reading surface of the card are blocked by the flange 42 which rests on card 31.

In order to hold the alidade and compass card in adjusted position, a securing member or nut 63 is threaded on the end 38 of the nipple 36 and bears on the alidade to hold the latter securely but removably, against the card 31 at the flange 42 and also against the circumferential enlargement 37 of the nipple 36. A further securing member or nut 64 is threaded to the exterior of that portion of the tube 26A which extends above the nipple 36 to hold the nipple 36 upon the tube 26A and thus secure the alidade and the card 31 to the gimbal ring 11 and the well member 15.

55 The illumination is controlled by a plunger 61, slidable within the tube 26A. The plunger continues through the tube 26A and into the lower end of the hollow post 26 where it cooperates with and controls the switch 21. The plunger 61 may continue through the base of the well member 15 to come in contact with any provided micro-switch or may, as shown in Figure 2, come in contact with the plunger of the switch 21 within the lower end of the hollow post 26.

The switch 21 may be of any desired construction, as for example a micro-switch such as shown in Patent No. 1,960,020, dated May 22, 1934, or may, if desired, be arranged to provide such selective control of the current as will govern, within limits, the intensity of the light at the sight opening 45. The upper end of switch plunger 61 has an operating finger piece 65, which not only serves for operating the plunger 61 to control the switch, but provides a rest for the sighting vane 50 when the latter has been turned down into inoperative position. Vane 51 is supported in

inoperative position on securing member 64, as shown in Figure 2.

The card 31 which is an important feature of the present invention is as previously pointed out, preferably of metal and of course opaque. It is accurately centered and supported both centrally and at its outer edge. The card is indestructible, which is a decided advantage over the conventional glass or transparent card in the usual type of pelorus, and is easily dismounted for cleaning or other purposes. It will be particularly noted that the means for illuminating the card as compared with the usual method of illuminating and directing the light through a glass or transparent card, has the distinct advantage of avoiding any error in viewing the markings of the card with respect to the sight wire, such as reflected or false images, found with use of a glass or transparent card, and also avoids the incidental parallax found with the use of a glass or transparent card. Since illumination is provided for only a very small area of the card and the light source is otherwise shielded, the small amount of light which escapes is only visible within the immediate vicinity of the instrument. This is particularly advantageous when the pelorus is used out in the open on the decks of ships which desire to travel without any light whatsoever revealing the ship's position.

The operation and use of the improved pelorus does not differ materially from conventional uses, and needs no detailed description.

In general detail and as productive of more efficient coincident operation, it will be appreciated that the relatively large central bearings of the card and of the alidade, together with the edge support of the card, lend to unusual steadiness of the parts in operation. The means for securing these parts separatively and relatively is so simplified as to provide for convenient necessary operative steps while facilitating independent removal for cleaning. Furthermore the immediately adjacent relation of the card graduations and the alidade sight wire obviously insures more accurate reading with less liability of error such as resulting from parallax.

It is contemplated that the light-directing surfaces, particularly that of the alidade, will be sufficiently reflected through proper finish of metal surfaces. However, if desired, the said surfaces, including the inner well surface, may be painted a glossy white. The under surface of the alidade center 39 may, as shown in Figure 4, be provided with light-directing recesses or deflectors 66 channelled within the under surface and shaped and disposed to assist in directing the light passing through the openings 35 in the card, toward the light channel 47 of the alidade.

It will be noted that the parts are so fitted together as to provide a waterproof housing for the light source and to shield the light-transmitting parts from spray or salt deposit.

The particular arrangement of the weight 25 moves the center of gravity of the parts carried by the inner gimbal ring below the pivot axis of such parts, thus providing a materially-increased steadiness of operation.

What is claimed as new is:

1. An instrument of the pelorus type, including a gimbal ring, a well rigid with and depending from the ring, a light source in the well, the upper end of the well being open and presenting an

annular edge, a compass card of metal adapted to overlie and bear on the annular edge of the well, the edge of the card being in bearing contact with the ring, the card within the area of the annular edge being formed with concentric rings of openings for light passage therethrough, an alidade mounted above the card and having a center formed to surround said card openings and overlie said card openings, said alidade having diametric arms integral with the center and formed with sight openings, one of said arms being formed in its lower surface with a channel leading from the sight opening of that arm to and within the alidade center for light communication with the openings in the card.

2. A construction as defined in claim 1, wherein the channel in the alidade arm is of arcuate cross-section, and wherein the defining edges of the channel in the alidade rest on the card to prevent card illumination beyond such arm.

3. A construction as defined in claim 1, wherein a casing is secured to and extends below the well, a switch secured to said well and arranged in said casing, a manually-operable switch controlling element extending through the well, card, and alidade center, and means concentric with said element for securing the card and alidade rigidly in any desired relation relative to the ring and to each other.

4. In a pelorus including a support, an opaque card having calibrations on its upper surface, said card being mounted on said support, a light source below said card, said card having light passages therethrough adjacent its center, an alidade, said alidade having an opaque recessed hub portion rotatable about the center of the card, said hub overlying the light passages of said card and being peripherally interrupted to direct the light passing upwardly through said card to a single sector thereof, said alidade also including a pair of radial arms extending in opposite directions from said hub, one of said arms being in registry with the interrupted portion of said hub and serving to shield the sector of light except at the calibrated portion of the card.

5. In a pelorus including a support, an opaque card having marginal calibrations, said card being mounted on said support for rotation in a horizontal plane, a housing mounted on said support below said card, the top of said housing and the under side of said card defining therebetween a light seal, a light bulb in said housing, a normally open micro switch controlling the flow of current to said light bulb, said micro switch being located in said housing, a switch operating rod extending upwardly from said micro switch through the center of said card to a point thereabove, said card having light passages therethrough adjacent its axis of rotation and an alidade, said alidade having an opaque hub portion recessed on its under side, said hub portion overlying the center of the card with its recessed portion registering with the light passages through the card, said hub portion being peripherally interrupted to confine the light from the recess to a sector of said card, said alidade also including a pair of radial arms extending in opposite directions from said hub, one of said arms being in registry with the interrupted portion of the hub and serving to shield the sector of light except at the marginal portion of the card.
